UNITED STATES PATENT OFFICE.

WILLIAM H. COOK, OF INDIANAPOLIS, INDIANA.

ENVELOP-MACHINE.

1,142,402.

Specification of Letters Patent. Patented June 8, 1915.

Application filed February 6, 1914. Serial No. 816,891.

To all whom it may concern:

Be it known that I, WILLIAM H. COOK, a citizen of the United States, residing at Indianapolis, in the county of Marion and State of Indiana, have invented a new and useful Envelop-Machine, of which the following is a specification.

The object of my invention is to produce an improvement in a common form of envelop machine by means of which the completed envelopes may be accurately discharged from the forming mechanism, said ejecting mechanism being reduced in its parts to a minimum number of readily accessible and maintainable members.

The accompanying drawing, which is a vertical section, illustrates my invention.

In the drawing, 10 indicates the forming box to which the previously cut blank is delivered by the delivery hook 11. Coöperating with the forming box 10 is the plunger 12 beneath which the blank is delivered and which serves to drive the blank into the forming box 10, as indicated by the dotted lines 13, which dotted lines show the plunger and envelop blank in an intermediate position passing toward the forming table 15 which is arranged at the lower end of box 10. The table 15 is pivoted at 16 and is controlled in its movement about pivot 16 by a pitman 17 which leads to a controlling cam of common form. Coöperating with the table 15 are flap folders 17, 18 and 19 which are grouped around the box 10 and operated in the usual manner to fold the flaps of the envelop blank down upon the main body, the folders 17 and 19 coming down squarely upon the table 15 so as to seal the adjacent flaps, and the folder 18 also coming down squarely so as to produce a sharp fold in forming the inlet flap, but a sealing of this entry flap is prevented both by the shortness of the flap folder 18 and also by means of a draw-off finger 20 which is projected in front and beneath the gummed edge of the entry flap. The various elements thus far described are in common use in envelop machinery and are therefore shown only in a fragmentary way in the drawings. The table 15 is provided near its rear edge with one or more slots 22 which extend through the table and these grooves 22 extend to but not through the rear edge of the table so that an ejector finger 23, one of which is provided for each groove 22, may, when the table 15 is swung downwardly about pivot

16, to the position indicated in dotted lines, project through the groove 22 at first beyond the rear edge of the envelop so as to thus come up behind the completed envelop 60 which lies upon the table. The ejector finger 23 is slightly hooked at its free end, as shown, and is carried upon a bracket 25 which is vertically adjustable by means of a clamping screw 26 upon a bracket 27 carried by the main frame of the machine, said bracket 27 being horizontally adjustable by means of a clamping screw 28. The ejector finger 23 is pivoted at 29 upon bracket 25 and is normally held in the position shown 70 in full lines by the spring 30. Carried by the ejector finger 23 is a cam 31, the normal position of which is determined by the adjustable stop 32 carried by bracket 25 and this cam 31 is so formed as to be operated 75 upon by a finger 33 which is carried by the table 15.

By proper adjustment of the two brackets 27 and 25 the pivotal point 29 of the ejector finger 23 may be brought accurately to such 80 position as is necessary and desirable for proper operation of the ejector finger and normally this ejector finger lies with its upper hooked end below the working surface of the table 15 and in the lower rear end of 85 the L-shaped slot 22. As soon as the envelop has been completed, the flap folders 17, 18 and 19 are withdrawn and table 15 is moved downwardly toward the position indicated in dotted lines, the finger 20 following the 90 table and, as its lower end projects beneath the entry flap of the envelop, the envelop is slid forwardly (to the left in the drawing) upon the table after the upper forward edge of the table has passed below the adjacent 95 stationary parts of the machine, and at this time the finger 33, which is carried by the table 15, comes into engagement with the cam 31 and swings the ejector finger 23 upon its pivot 29 so as to positively eject the completed envelop from the table 15 beneath the 100 stationary supporting table 35. In the actual machine this ejection takes place toward and to an envelop carrier in which the envelop is held until the gum upon the entry 105 flap is properly dried, but as that mechanism forms no part of my present invention, it has been omitted from the drawings.

It has heretofore been common practice to carry the slots 22 clear to and through the rear edge of the forming table and consequently the folding flap 17 always pressed

the front face of the envelop into each slot and produced a quite noticeable crease in the lower edge of the finished envelop.

It will be noticed that, in my present construction, the slots 22 are stopped short of the rear edge of the forming table and consequently, when the folding flap 17 is brought down upon the envelop there is a continuous surface beneath it where the fold 10 is formed and there is no creasing of the front face of the envelop into its slots 22.

I claim as my invention:

1. In an envelop machine, the combination with envelop-forming mechanism comprising a movable forming table having a transverse slot formed through its working face near its rear edge, of a swinging ejector finger arranged to cooperate with said work table through the slot thereof, a cam carried by said ejector finger, a cam operating finger carried by the work table and coöperating with said finger cam to drive said finger through its ejecting motion when the work table is moved through its envelop 25 delivering movement, and draw-off means coöordinated with the work table and ejector finger for engaging the envelop upon the table when the table moves in discharging direction to advance said envelop to uncover the rear end of the work table slot 30 prior to the projection of the ejector finger above the working face of the work table.
2. In an envelop machine, the combination of a forming table and folding flaps 35 coöperating with the edges thereof, said table having a slot formed therethrough for an ejector finger but stopping short of the adjacent folding flap so as to leave a continuous table edge immediately beneath the 40 said flap, an ejector finger, means for operating said finger into and along the slot, and draw-off means coöordinated with the work table and ejector finger for engaging the envelop upon the table when the table 45 moves in discharging direction to advance said envelop to uncover the rear end of the work table slot prior to the projection of the ejector finger above the working face of the work table.
3. In an envelop machine, the combination with coöordinated folding members for folding the envelop, of a swinging work

table with which said folding members are coöordinated for the folding operation, said swinging table having a fixed pivot and a 55 slot through its working face falling short of the edges of the table, an ejector finger arranged below the table in position to be projected through and along said slot by the swinging action of the work table away 60 from the folding members, and draw-off means coöordinated with the work table and ejector finger for engaging the envelop upon the table when the table moves in discharging direction to advance said envelop 65 to uncover the rear end of the work table slot prior to the projection of the ejector finger above the working face of the work table.

4. In an envelop machine, the combination with coöordinated folding members for folding the envelop, of a swinging work table with which said folding members are coöordinated for the folding operation, said swinging table having a fixed axis and a 75 slot through its working face, a rock shaft arranged below the table substantially parallel with the axis thereof, an ejector finger carried by said rock shaft in alinement with the plane of movement of the work table 80 slot and normally lying beneath the work table surface, interengaging members carried by said work table and said ejector finger whereby the final swinging movement of the work table will produce movement of 85 the ejector finger lengthwise of the work table slot subsequent to the projection of the end of said ejector finger above the work table surface, and draw-off means coöordinated with the work table and ejector 90 finger for engaging the envelop upon the table when the table moves in discharging direction to advance said envelop to uncover the rear end of the work table slot 95 prior to the projection of the ejector finger above the working face of the work table.

In witness whereof, I have hereunto set my hand at Indianapolis, Indiana, this 4th day of February, A. D. one thousand nine hundred and fourteen.

WILLIAM H. COOK.
